UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 14, 1923. Serial No. 657,291.

This invention relates to manifolding typewriting machines of the continuous billing type, in which a composite sheet or web is fed around a cylindrical platen, the web comprising several plies of work-sheets having successive corresponding forms printed thereon, said plies being sometimes separated from each other and sometimes joined at their side edges to form a fan-folded web, the various plies having carbon-sheets interleaved therebetween which are displaceable at intervals along the web to fresh sets of forms. The invention relates more particularly to means to facilitate the relative displacing or shifting between the carbon-sheets and the work-sheets.

In practice, it has been found impracticable to shift the carbon-sheets relatively to the work-sheets while the carbon-sheets and the work-sheets are bent short, as, for example, around the platen which is of comparatively small radius. In the Underwood continuous billing machine, shown in the patent to Wernery & Smith, No. 1,132,055, dated March 16, 1915, the platen is displaceable upwardly by means of a swing frame, so that that portion of the web containing the carbon-sheets may be straightened out preparatory to displacing the carbon-sheets relatively to the work-sheets. The carbon-sheets extend forwardly from a carbon-carrier, which may be moved rearwardly while the work-sheets are moved forwardly to a gage, after which the platen may be lowered to its normal typing position. The typed set of forms may then be severed and the typing of a fresh set of forms may proceed.

It has been found that that portion of the web containing the carbon-sheets may be so conditioned that there may be caused a relative shifting without lifting the platen, in other words, while the platen remains in its usual typing position. To this end, there has been proposed a curved table at the rear of the platen over which the web is conducted and from which it extends tangentially to the platen. One form of this arrangement is shown in my co-pending application, Serial No. 642,961, filed June 2, 1923 (now Patent No. 1,574,215, dated February 23, 1926), in which the table forms part of a cylinder of a comparatively large radius. The table always occupies a fixed position relatively to the platen, and a car-

bon-carrier travels over said table toward the platen during line-spacing operations. After a form has been completed, the web may be withdrawn around the platen by moving the carbon-carrier over said table and away from the platen until the leading edges of the carbon-sheets have been freed from said platen. The work-sheets are then fed forwardly while the carbon-sheets are held to thus strip the carbon-sheets from the typed set of forms and bring them to a fresh set or untyped set of forms.

In the present invention a curved table and a carbon-carrier are used to condition the web for a carbon-displacing operation. An object of the present invention is to lower said table after a carbon-displacing operation, so that there may be created in the web behind the platen sufficient slack which may readily be taken up during the line-spacing of said web around the platen, thus avoiding any hindrance to the web during line-spacing operations, which may be occasioned without slack in said web.

In the present invention, after a form has been typed and it is desired to prepare the web for a carbon-shifting operation, the curved table is rotated about its pivot to thus take up the remaining slack in the web and also draw the web from a source of supply as the table approaches its operated position. According to the extent to which the web has been fed around the platen, the carbon-carrier will also be drawn upwardly from its normal position during the upward rotation of the table. After the table has reached its operated position, the feed-rollers may be cast off and the carbon-carrier may then be actuated to return it to its normal position to thus draw the web around the platen until the leading edges of the carbon-sheets are freed from the platen. The feed-rollers are then thrown on, and while the table is held in its operative or raised position, which may be by means of a latch, and the carbon-carrier is held in its normal position to thus hold the carbon-sheets, the platen may be rotated to advance the work-sheets relatively to the carbon-sheets, a gage being provided at the introductory side of the platen to determine the extent of relative shifting movement. After the work-sheets have been shifted, the curved table may be returned or lowered to its normal position,

thus producing slack in the web, which may be taken up during the line-spacing of the web around the platen. The web is then fed to bring the leading edges of the work-sheets to a second gage to thus bring the carbon-sheets to the printing point and the bottoms of the typed forms to a knife where they may be severed. Typing of the fresh set of forms may then be proceeded with.

10 Operating handles are provided for the web-conditioning table and the carbon-carrier, and are supported on a sub-carriage connected to travel with the typewriter carriage, said sub-carriage supporting also said table and said carbon-carrier.

15 Other features and advantages will hereinafter appear.

In the accompanying drawings,

20 Figure 1 is a part sectional side view of an Underwood typewriting machine, showing the invention applied thereto, the parts being in position during typing operations.

25 Figure 2 is a top plan view of the machine, with the parts in the position shown in Figure 1.

30 Figure 3 is a view similar to Figure 1, but shows the web-conditioning table in its raised position and the carbon-carrier drawn forwardly thereby, the feed-rollers still holding the web against the platen.

35 Figure 4 is a view similar to Figure 3, but shows the feed-rollers released and the carbon-carrier returned to its normal position to withdraw the web around the platen 35 to free the carbon-sheets from the platen preparatory to advancing the work-sheets.

40 Figure 5 is a view similar to Figure 4, with some of the parts omitted, the parts occupying the same positions as in Figure 4, except the feed-rollers which are thrown on and have assisted in advancing the work-sheets, with respect to the carbon-sheets, to the first gage.

45 Figure 6 is a view similar to Figure 4, but shows the slack produced in the web behind the platen after the table has been lowered, the web having been fed to the second gage to bring the carbon-sheets to the printing point and the bottoms of the 50 typed forms to the knife where they may be severed.

55 Type-bars 10 strike against the front of a revolute platen 11, which is journaled in the usual manner in a platen-frame comprising ends 12 and a rear paper-shelf 13. The usual front and rear feed-rolls 14 run on the under side of the platen. They may be released, or thrown from the platen, by means of a finger-piece 15, connected by a 60 link 16 to an arm 17, fast on a shaft 18. The shaft 18 is provided with flats, against which arms 19, forming part of levers 20, are held by spring-pressure. The levers 20 are pivoted on a shaft 21, so that, when 65 the finger-piece 15 is actuated, and the arms

19 spread apart by turning of the shaft 18, the levers 20, which support the pressure-rolls, are rocked on the shaft 21 to release the rolls. This roll-releasing structure is that commonly found in the standard Underwood typewriting machine.

70 The work-web, usually comprising superposed plies 22 (which may be separate or which may form a fan-fold), is drawn up from a supply-spool, or from a zigzag 75 folded pile (not shown), but which may be contained in a receptacle arranged in the rear of the typewriting machine and its stand 23. As the plies of the work-web rise from the supply at 24, 80 they first pass through a carbon-carrier 25; and are there interleaved with the carbons 26. Each of the carbons 26 has its rear end attached to one of two blades 27, carried by standards 28 on the ends of a plate 85 29. The plate 29 is secured to a bar 30, supported at its ends by a pair of arms 31, one on each side of the machine, loosely pivoted at 32 on stub-shafts 33, journaled in the side pieces 34 of a frame or sub-carriage which is connected to the platen-carriage for movement with the latter in letter-feed and return directions. The purpose of the pivotal mounting of the carbon-carrier will hereinafter more fully appear.

90 The side pieces 34 of the sub-carriage, which pieces are shown, in Figures 1 and 3, as of general triangular formation, are tied together at the front of the sub-carriage by a bar 35, which is secured by screws or rivets 36 to brackets 37, in turn secured at 95 38 to the usual rear cross bar or tie 39 of the platen-carriage. The platen-carriage is supported in the usual way upon a rail 40 on the main frame 41 of the machine for 100 movement in letter-feed and return directions. The sub-carriage side pieces 34 are connected at the rear of the sub-carriage by a bar or tie 42, from which depend a pair 110 of brackets 43, having rollers 44 thereon which ride on a rail 45 supported on the rear of the table 23 which supports the machine. Ears 46, offset from the brackets 43 under the rail 45, serve to hold the sub-carriage down on the table 23.

115 When the parts are in typing position, the work-plies 22, interleaved with the carbons 26, pass upward from the carbon-carrier over a roller 49, and thence forward to and over a roller 50, journaled at 51 in the side plates 34 of the sub-carriage, above and at the rear of the paper-table 13; the roller 50 being so located that the composite web may pass tangentially therefrom, down over the table 13 to the rear under face of the platen, whence it is guided around the platen, up across the printing line, and along and in front of a staff 52, to which is adjustably secured, by means of a thumb-screw 53, a gage 54, the purpose of which 125 130

gage will hereinafter more fully appear. Between the rear roll 49 and the front roll 50 the composite web is in the form of a slack 55, which is sufficient to permit of line-space feed of the composite web with the platen, in the typing operation, without complete elimination of the slack before the typing operation itself is completed.

After typing on a form-section of the web 10 is completed, the web is to be conditioned for relative shift of the carbons and work-webs to clear the carbons from the typed form-sections and to set the same into the succeeding untyped form-sections. The first 15 step in this conditioning of this web is to draw out all slack in the web, so that, in the shifting operation, the carbons and web-plies will not become fouled with one another; and to lay the same smoothly on a 20 surface having no abrupt turns therein which might cause binding and injury of the web-plies and carbons or impede their easy movement. This preliminary conditioning of the web is effected while the feed- 25 rollers 14 hold the forward part of the web against movement on the platen. The means for effecting this preliminary conditioning comprise a table 56, which is of long arcuate formation, and which is secured by 30 screws or rivets 57 to ears 58 on the arms 59, 60 and 61 of a spider or frame secured to the stub-shafts 33 for pivotal movement around the axis 32 on the sub-carriage. It will be understood from Figure 2 that there are two 35 sets of arms 59, 60 and 61, one set at each side of the arcuate table 56, so that the latter is, in effect, a section of a drum or cylinder, journaled at its ends in the side plates 34 of the sub-carriage, so as to have movement 40 with the platen-carriage in letter-feed and return directions. The roller 49, over which the composite web first passes after leaving the carbon-carrier, as shown in Figure 1, is journaled at 62^a in the arms 59 of the 45 rotary table; and the arms 59, 60 and 61 serve as guards, between which the side edges of the slack portion 55 of the web, in the Figure 1 position of the latter, is held during the travel of the platen-carriage. It 50 will also be noted that the convexity of the table 56, in its Figure 1 position, provides space for the slack 55. The Figure 1 position of the table is determined by the engagement of the left-hand arm 61 of the 55 rotary table with a pin 63 on the left-hand side piece 34 of the sub-carriage.

For rotating the table 56 from Figure 1 to Figure 3 position, there is provided a handle 64, which is unitary with a rack 65, and which is pivoted at 66 to the left-hand side plate 34 of the sub-carriage. The rack 65 meshes with a pinion 67, journaled at 68 to the same side piece 34; and the pinion 67, in turn, meshes with a pinion 69, fast on the 65 stub-shaft 33, which forms the left-hand

journal of the table 56, and to which, as aforesaid, the table 56 is made fast. It follows from the above that, when the operating arm 64 is drawn forward, from Figure 1 to Figure 3 position, the table 56, by 70 means of the rack 65, pinion 67, and pinion 69, is swung clockwise, looking from the left, from Figure 1 to Figure 3 position. The table 56 is arrested in its Figure 3 position by the engagement of the right-hand table-supporting arm 59 with a stop-pin 73 on the right-hand side piece 34 of the sub-carriage. For holding the table 56 against accidental displacement, in Figure 3 position, there is provided a spring-latch. This latch consists 75 of a bell-crank lever 71, pivoted at 72 to the right-hand table-arm 59, and having a nose 74 adapted to be snapped over the stop-pin 73. A spring 75, connected at one end to the latch-lever 71, and at its other end to 80 the table-arm 59, holds the latch in a normal position, determined by a stop-pin 71^a on the table-arm 59, and returns the latch to such stop-pin, after movement of the latch, upon 85 release of the latch to the action of the spring 75. When the table comes to Figure 90 3 position, the pin 73 cams the latch backward against the action of the spring 75, to permit the nose of the latch to pass the stop-pin. When the nose of the latch is past 95 the stop-pin, the spring 75 acts to lock the table in place. It is noted, upon reference to the drawings, that the nose of the latch, where it hooks over the stop-pin, is of such 100 shape as to cause the latch to be cammed free of the stop-pin when the lever 64 is thrown upward, from Figure 3 position, to return the table to its normal, Figure 1, position.

During the throw of the table 56 to Figure 105 3 position, the roller 49 serves as an anti-friction device, for drawing out the web, without injury to the latter. In the Figure 3 position of the table, it will be noted that the carbons and work-webs lie smoothly 110 thereon, so that subsequent shift of the work-webs and carbons may be effected without crumpling or injury to either the carbons or the work-webs. In this connection, it will be noted that, during the movement to Figure 115 3 position, the web is at all times tangential to the table at the rear of the latter, and that, when the table is in Figure 3 position, the composite web extends tangentially from the forward end of the table to the platen. All sharp bends in the web are thereby 120 avoided.

It has been stated that, during this Figure 125 1 to Figure 3 movement of the table, the pressure-rolls 14 remain applied to the platen, so that the web-plies and carbons are held at the forward part thereof. The web-plies 22, not being secured at their rear, may be drawn from their supply at the rear a distance sufficient to accommodate the web to the Figure 3 position of the table. Since, 130

however, the carbons are secured to the carbon-carrier, the latter should be free to move upward, during the Figure 1 to Figure 3 movement of the table, a distance sufficient 5 to accommodate the carbons to the Figure 3 position of the table. The loose pivoting of the carbon-carrier permits the latter to be swung by the pull of the table 56 on the web. The distance to which the carbon-carrier will be swung during the movement 10 of the table, from Figure 1 to Figure 3 position, depends upon the amount of slack 55 or length of web between the carbon-carrier and the roll 50 at the front of the 15 sub-carriage; and this, in turn, depends upon the amount of line-space feed the web 20 has had during the typing of the leading form-section thereof. This Figure 1 to Figure 3 movement of the carbon-carrier may, therefore, be a variable movement. The relative movement of the work-webs 25 and carbons, in the form-to-form shift of the latter, is, however, a movement which is determined by, and equal to, the length of the form-sections.

Preliminary to the actual form-to-form shift of the work-webs, with respect to the carbons, the pressure-rolls 14 are released, and the carbon-carrier, with the carbons and 30 work-webs, is moved from Figure 3 position to another, Figure 4, position, to clear the carbons from the platen, so that, as presently to be described, the work-webs may thereafter be fed forward by the platen and the 35 pressure-rolls without forward feed of the carbons. This movement of the carbon-carrier, with the carbons and work-webs, to release the carbons from the platen, and to fix the position of the carbons for a subsequent 40 forward feed of the work-plies with respect thereto, is accomplished by the following means.

The right-hand carbon-carrier arm 31 has a rack 77 formed thereon, concentric with 45 its axis of rotation 32. Journaled at 78, on the right-hand side piece 34 of the sub-carriage, is a pinion 79, in mesh with the rack 77. Also journaled at 80, on the same sub-carriage side piece, is a rack 81, to which is affixed an operating lever 82. In the movement of the table 56, from 50 Figure 1 to Figure 3 position, and consequent movement of the carbon-carrier, as aforesaid, from Figure 1 to Figure 3 position, the rack 77, acting through the pinion 79 and rack 81, throws the carbon-carrier-operating lever downward, as indicated in the drawings, thereby setting the same for the stroke thereof which is to release the carbons from the platen by retraction of the web. To return the carbon-carrier to its 55 normal, Figures 1 and 4, position, and release the carbons from the platen, preliminary to actual form-to-form shift of the work-webs, with respect to the carbons, the

handle 82 is swung up, as indicated in Figure 4. At this time the table 56 is held locked in Figure 3 position, and the handle 82, acting through the rack 81, pinion 79, and rack 77, moves the carbon-carrier downward, with respect to the table. A stoppin 70 83, on the left-hand sub-carriage side piece 34, by engagement with the left-hand carbon-carrier arm 31, determines the normal, Figures 1 and 4, position of the carbon-carrier, and determines the throw of the latter, from Figure 3 to Figure 4 position, to release the carbons from the platen. The web being laid out smoothly on the table 56, the Figure 3 to Figure 4 movement of the 80 web is easily effected.

After the web is in Figure 4 position, the form-to-form shift of the work-plies, relative to the carbons, may be effected, by forward feed of the work-plies around the 85 platen a distance equal to one form-length. For effecting such forward shift of the work-webs, it is merely necessary to reapply the feed-rolls 14 and to turn the platen by means of one of the hand-knobs 84 or line-space wheel 85, ordinarily found on the platen-axle. During this operation, the hand-lever 82 is held by the operator, in Figure 4 position, to prevent advance of the carbons with the work-plies. The lower 90 end 86 (see Figure 5) of an arm 87, unitary with the gage 54, serves to determine, by the registration therewith of the leading ends of the work-plies, the amount of advance of the work-plies required to properly position the carbons in the next untyped form-sections of the work-plies, and to clear the carbons of the leading typed form-sections for detachment of the latter.

It remains then to advance the composite web to position wherein such detachment of the leading typed form-sections may be effected, and to position the web for commencement of typing on the next untyped form-section thereof. It is for this purpose that the 105 gage 54 is provided, as shown in Figure 6. The movement of the composite web to bring the leading ends of the work-webs to the gage 54 is effected by a further forward 110 rotary movement of the platen. Preliminary to such further forward rotary movement of the platen, and in order that the carbons may be advanced with the work-plies during such movement, and without movement of the carbon-carrier, the handle 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 return of the latter to Figure 1 position, the rear edge 56^a of the table may be curved inward.

When the leading edges of the leading typed form register with the gage 54, the rear edges of the leading typed form register with the cutting edge of a blade 88, so that, as indicated in Figure 6, the typed form-section may be severed from the rest 10 of the web by drawing the web against the blade. The blade 88, as shown in Figure 2, is secured at its ends to brackets 89, in turn, secured to the end pieces 12 of the platen-frame. The brackets 89 also serve to support 15 a cross-plate 90, to which the gage-staff 52 is centrally secured at 91. After detachment of the typed form-section, as indicated in Figure 6, or without detaching such form-section, typing on the next form 20 may be commenced.

It will be noted, on reference to Figures 1 and 3, that in all positions of the rotary table or shell 56, and of the carbon-carrier, both these elements are above the platform 25 which supports the machine, so that the platform may be extended horizontally rearward to the support thereon for the sub-carriage. It will also be noted that no space between the rotary table and the machine is required for the slack in the web; the 30 concavity of the table or shell itself providing the space for the slack. Since the table or shell and the carbon-carrier require no more space in the Figure 1 position 35 than in the Figure 3 position thereof, and since the means for actuating these devices may, in effect, be located within the shell or space which the latter occupies; and since the web may be led directly and substantially vertically up onto the carbon-carrier 40 or table, the whole presents an extremely compact structure, requiring no space below the machine-platform, and requiring a space only slightly greater than the diameter of the rotary table or shell at the rear of the 45 machine.

Variations may be resorted to within the scope of the invention, and portions of the improvements may be used without others.

Having thus described my invention, I 50 claim:

1. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise as to provide a slack in the untyped part 55 thereof when the web is in position for commencement of typing on one of its form-lengths, such slack being sufficient to permit of line-feed of the composite web in the typing of a form-section without pull on the carbon-holder, means for conditioning the 60 web for shift of the carbons to an untyped form-section of the webs, comprising means for drawing upon the web in a crosswise direction between the carbon-holder and the platen, means for holding the web against 65 rearward displacement on the platen while so drawing upon the web, and a carrier for the carbon-holder mounted for free movement with the web as the latter is drawn upon as aforesaid.

the web for shift of the carbons to an untyped form-section of the webs, comprising means for drawing upon the web in a crosswise direction between the carbon-holder and the platen, means for holding the web 70 against rearward displacement on the platen while so drawing upon the web, and a carrier for the carbon-holder mounted for free movement with the web as the latter is drawn upon as aforesaid. 75

2. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise as to provide a slack in the untyped part thereof when the web is in position for commencement of typing on one of its form-lengths, such slack being sufficient to permit of line-feed of the composite web in the typing of a form-section without pull on the carbon-holder, means for conditioning the web for shift of the carbons to an untyped form-section of the webs, comprising means for drawing upon the web in a crosswise direction between the carbon-holder and the platen, means for holding the web 80 against rearward displacement on the platen while so drawing upon the web, a carrier for the carbon-holder mounted for free movement with the web as the latter is drawn upon as aforesaid, 85 and means for moving the carrier relatively to such web-drawing means for retracting the web over such web-drawing means after the latter is in effective position, and after the web has been released for rearward movement around the platen, to clear the carbons from the 90 platen. 95

3. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise as to provide a slack in the untyped part thereof when the web is in position for commencement of typing on one of its form-lengths, such slack being sufficient to permit of line-feed of the composite web in the typing of a form-section without pull on the carbon-holder, means for conditioning the 100 web for shift of the carbons to an untyped form-section of the webs, comprising means for drawing upon the web in a crosswise direction between the carbon-holder and the platen, means for holding the web against rearward displacement on the platen while so drawing upon the web, a carrier for the carbon-holder mounted for free movement with the web as the latter is drawn upon as aforesaid, 105 and means for moving the carrier relatively to such web-drawing means for retracting the web over such web-drawing means after the latter is in effective position, and after the web has been released for rearward movement around the platen, to clear the carbons from the 110 platen. 115

6
to such web-drawing means for retracting the web over such web-drawing means after the latter is in effective position, and after the web has been released for rearward movement around the platen, to clear the carbons from the platen, and means for holding the carbon-carrier with the carbons in such retracted position, and the web-drawing means in its effective position, while the work-webs 10 are fed forward around the platen to effect the aforesaid shift of the same with respect to the carbons.

4. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise 20 as to provide a slack in the untyped part thereof when the web is in position for commencement of typing on one of its form-lengths, such slack being sufficient to permit of line-feed of the composite web in the 25 typing of a form-section without pull on the carbon-holder, means for conditioning the web for shift of the carbons to an untyped form-section of the webs, comprising means for drawing upon the web in a crosswise 30 direction between the carbon-holder and the platen, means for holding the web against rearward displacement on the platen while so drawing upon the web, a carrier for the carbon-holder mounted for free movement 35 with the web as the latter is drawn upon as aforesaid, means for moving the carrier relatively to such web-drawing means for retracting the web over such web drawing means after the latter is in effective position, and after the web has been released for 40 rearward movement around the platen, to clear the carbons from the platen, means for holding the carbon-carrier with the carbons in such retracted position, and the web-drawing 45 means in its effective position, while the work-webs are fed forward around the platen to effect the aforesaid shift of the same with respect to the carbons, and means whereby the web-drawing means may be 50 returned to normal position to re-establish slack in the web while the carbon-carrier remains in its retracted position, so that the composite web may thereafter be fed to position for commencement of typing without 55 movement of the carbon-carrier.

5. In a typewriting machine, a revoluble platen, means for holding work-webs, composed of a succession of forms, and carbons interleaved therewith, for line-space feed 60 with the platen, a holder to which the carbons are anchored at their rear, means for supporting the composite web in such wise as to provide a slack in the untyped part thereof when the web is in position for commencement of typing on one of its form- 65 lengths, such slack being sufficient to permit of line-feed of the composite web in the

lengths, such slack being sufficient to permit of line-feed of the composite web in the typing of a form-section without pull on the carbon-holder, means for conditioning the web for shift of the carbons to an untyped 70 form-section of the webs, comprising a pivotally-mounted table having a curved surface adapted to be swung against the web to draw upon the same while the web is held against retractive displacement around the platen, and a carrier for the carbon-holder pivotally mounted for movement with the web as the latter is drawn out by the table.

6. In a typewriting machine, a revoluble 80 platen, means for holding work-webs, composed of a succession of forms, and carbons interleaved therewith, for line-space feed with the platen, a holder to which the carbons are anchored at their rear, means for 85 supporting the composite web in such wise as to provide a slack in the untyped part thereof when the web is in position for commencement of typing on one of its form-lengths, such slack being sufficient to permit of line-feed of the composite web in the 90 typing of a form-section without pull on the carbon-holder, means for conditioning the web for shift of the carbons to an untyped form-section of the webs, comprising a 95 pivotally-mounted curved table, a carrier supporting the carbon-holder for movement of the latter over and along the surface of the table, means for swinging the table against the web to draw the latter out on the surface of the table, and means for holding the web against retractive movement 100 around the platen during such swing of the table, the carbon-carrier being free to move relatively to the table with the carbons and web during such swing of the table.

7. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise 110 as to provide a slack in the untyped part thereof when the web is in position for commencement of typing on one of its form-lengths, such slack being sufficient to permit of line-feed of the composite web in the 115 typing of a form-section without pull on the carbon-holder, means for conditioning the web for shift of the carbons to an untyped form-section of the webs, comprising a 120 pivotally-mounted curved table, a carrier supporting the carbon-holder for movement of the latter over and along the surface of the table, means for swinging the table against the web to draw the latter out on the surface of the table, means for holding the web against retractive movement around 125 the platen during such swing of the table, 130

the carbon-carrier being free to move relatively to the table with the carbons and web during such swing of the table, means for holding the table in position with the web thus drawn out thereover, and means for retracting the carbon-carrier with the web along the table to clear the carbons from the platen when the web is released for retractive movement with respect to the platen.

10 8. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise as to provide a slack in the untyped part thereof when the web is in position for commencement of typing on one of its form-lengths, such slack being sufficient to permit of line-feed of the composite web in the typing of a form-section without pull on the carbon-holder, means for conditioning the web for shift of the carbons to an untyped form-section of the webs, comprising a rotatably-mounted convexly-curved table, inverted in its normal or typing position, means for revolving the same to draw out the web over the convex surface thereof, and 30 a carrier for the carbon-holder, movable with the web over the convex surface of the table.

9. In a typewriting machine, a revoluble platen, means for holding work-webs, composed of a succession of forms, and carbons interleaved therewith, for line-space feed with the platen, a holder to which the carbons are anchored at their rear, means for supporting the composite web in such wise as to provide a slack in the untyped part thereof when the web is in position for commencement of typing on one of its form-lengths, such slack being sufficient to permit of line-feed of the composite web in the typing of a form-section without pull on the carbon-holder, means for conditioning the web for shift of the carbons to an untyped form-section of the webs, comprising a rotatably-mounted convexly-curved table, inverted in its normal or typing position, means for revolving the same to draw out the web over the convex surface thereof, a carrier for the carbon-holder mounted to be freely moved over the table by the pull of the web thereon as the latter is drawn out by the table, means for holding the web against retractive movement around the platen during such movement of the table, and means for moving the carbon-carrier with the web over the table while the latter is held in effective position, to clear the carbons from the platen by retracting the web around the table and platen when the web is released for such retractive movement with respect to the platen.

10. In a continuous billing typewriting machine, the combination of a platen around which a composite web comprising plies of work-sheets, interleaved with carbon-sheets, may be fed, means for conditioning the web for a shift of the carbons relative to the work-plies, comprising a device adapted to be moved against the web to draw out the web behind the platen, and a carrier to which the carbons are anchored at their rear and which is movable by and with the web as the latter is drawn out.

11. In a continuous billing typewriting machine, the combination of a platen around which a composite web comprising plies of work-sheets, interleaved with carbon-sheets, may be fed, means for conditioning the web for a shift of the carbons relative to the work-plies, comprising a device adapted to be moved against the web to draw out the web behind the platen, a carrier to which the carbons are anchored at their rear and which is movable by and with the web as the latter is drawn out, and means for retracting the carbon-carrier while the web-drawing device is in effective position, to clear the carbons from the platen.

12. In a continuous billing typewriting machine, the combination of a platen around which a composite web comprising plies of work-sheets, interleaved with carbon-sheets, may be fed, means for conditioning the web for a shift of the carbons relative to the work-plies, comprising a device adapted to be moved against the web to draw out the web behind the platen, a carrier to which the carbons are anchored at their rear and which is movable by and with the web as the latter is drawn out, and means for holding the web stationary at a point thereof forward of the web-drawing device while the latter acts on the web.

13. In a continuous billing typewriting machine, the combination of a platen around which a composite web comprising plies of work-sheets, interleaved with carbon-sheets, may be fed, means for conditioning the web for a shift of the carbons relative to the work-plies, comprising a device adapted to be moved against the web to draw out the web behind the platen, a carrier to which the carbons are anchored at their rear and which is movable by and with the web as the latter is drawn out, means for holding the web stationary at a point thereof forward of the web-drawing device while the latter acts on the web, means for releasing the forward part of the web, and means for thereafter retracting the carbon-carrier while the web-drawing device is in effective position, to clear the carbons from the platen.

14. In a continuous billing typewriting machine, the combination of a platen around which a composite web comprising plies of work-sheets, interleaved with carbon-sheets,

may be fed, means for conditioning the web for a shift of the carbons relative to the work-plies, comprising a curved table, means for swinging the table against the web to draw out the web on the surface of the table, and a carrier to which the carbons are anchored at their rear and which is mounted for free movement along the table with the web as the latter is drawn out by movement 10 of the table.

15. In a continuous billing typewriting machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, 20 a carrier to which the carbons are anchored at their rear and which is mounted for free movement along the table with the web as the latter is drawn out by movement of the table, and means for retracting the carbon-carrier to draw the web backward over the table while the table is in effective position, to clear the carbons from the platen.

16. In a continuous billing typewriting machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, a carrier to which the carbons are anchored at their rear and which is mounted for free movement along the table with the web as 30 the latter is drawn out by movement of the table, and means for holding the web stationary at a point thereof forward of the table while the latter acts on the web.

17. In a continuous billing typewriting machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, a carrier to which the carbons are anchored at their rear and which is mounted for free movement along the table with the web as 40 the latter is drawn out by movement of the table, means for holding the web stationary at a point thereof forward of the table while the latter acts on the web, means for releasing the forward part of the web, and means for thereafter retracting the carbon-carrier while the table is in effective position to draw the web backward over the table, to clear the carbons from the platen.

65. 18. In a continuous billing typewriting

machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, a carrier to which the carbons are anchored at their rear and which is mounted 70 for free movement along the table with the web as the latter is drawn out by movement of the table, and means for retracting the carbon-carrier to draw the web backward over the table while the table is in effective position, to clear the carbons from the platen, the table and carbon-carrier being pivoted for movement on a common axis.

19. In a continuous billing typewriting machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, a carrier to which the carbons are anchored at their rear and which is mounted for free movement along the table with the web as the latter is drawn out by movement of the table, and means for retracting the carbon-carrier to draw the web backward over the table while the table is in effective position, to clear the carbons from the platen, the table being the segment of a drum or cylinder, it and the carbon-carrier being pivoted for rotation around the axis of the drum.

20. In a continuous billing typewriting machine, the combination of a platen around which a composite web comprising plies of work-sheets, interleaved with carbon-sheets, may be fed, means for conditioning the web for a shift of the carbons relative to the work-plies, comprising a curved table, means for swinging the table against the web to draw out the web on the surface of the table, a carrier to which the carbons are anchored at their rear and which is mounted for free movement along the table with the web as the latter is drawn out by movement of the table, and means for retracting the carbon-carrier to draw the web backward over the table while the table is in effective position, to clear the carbons from the platen, the table being the segment of a drum or hollow cylinder normally inverted to present the concavity thereof to the web and being rotatable around the axis of the drum in the web-driving operation, and the carbon-carrier being pivoted concentrically of the table.

21. In a continuous billing typewriting

- machine, the combination of a platen around which a composite web comprising plies of work-sheets, interleaved with carbon-sheets, may be fed, means for conditioning the web 5 for a shift of the carbons relative to the work-plies, comprising a curved table, means for swinging the table against the web to draw out the web on the surface of the table, a carrier to which the carbons are anchored at their rear and which is mounted 10 for free movement along the table with the web as the latter is drawn out by movement of the table, and means for retracting the carbon-carrier to draw the web backward over the table while the table is in effective position, to clear the carbons from the platen, the table being the segment of 15 a drum or hollow cylinder normally inverted to present the concavity thereof to the web and being rotatable around the axis of the drum in the web-driving operation, and the carbon-carrier being supported for movement near the convex surface of the table on arms pivoted concentrically of the table. 20 25 22. In a continuous billing typewriting machine, the combination of a platen around which a composite web comprising plies of work-sheets, interleaved with carbon-sheets, may be fed, means for conditioning the web 30 for a shift of the carbons relative to the work-plies, comprising a device adapted to be moved against the web to draw out the web behind the platen, a carrier to which the carbons are anchored at their rear and 35 which is movable by and with the web as the latter is drawn out, means for automatically locking the web-drawing device in its effective position, and means for retracting the carbon-carrier to draw the web rearward while the web-drawing device is so 40 locked, to clear the carbons from the platen. 23. In a continuous billing typewriting machine, the combination of a carriage, a platen on the carriage, around which a composite web, comprising plies of work-sheets, 45 may be fed with interleaved carbon-sheets, a sub-carriage to travel with the platen-carriage, a curved table in normally inverted position on the sub-carriage, means for rotating the table against the web to draw out the web on the curved surface of the 50 table, a carbon-carrier pivoted on the sub-carriage co-axially with the table for swinging movement independently of the table, and gearing on the sub-carriage for swinging the carbon-carrier to draw the web rearward over the table for clearing the carbons 55 of the platen. 24. In a continuous billing typewriting machine, the combination of a carriage, a platen on the carriage, around which a composite web, comprising plies of work-sheets, 60 may be fed with interleaved carbon-sheets, a sub-carriage to travel with the platen-carriage, a curved table in normally inverted 65 position on the sub-carriage, means for rotating the table against the web to draw out the web on the curved surface of the table, a carbon-carrier pivoted on the sub-carriage co-axially with the table for swinging movement independently of the table, a gear on the carbon-carrier, and gearing on the sub-carriage in mesh with the gear on the carbon-carrier for swinging the carbon-carrier to draw the web rearward over the table for clearing the carbons 70 of the platen. 25. In a continuous billing typewriting machine, the combination of a carriage, a platen on the carriage, around which a composite web, comprising plies of work-sheets, 75 may be fed with interleaved carbon-sheets, a sub-carriage to travel with the platen-carriage, a curved table in normally inverted position on the sub-carriage, means for rotating the table against the web to draw out the web on the curved surface of the table, a carbon-carrier comprising a pair of supporting arms pivoted on the sub-carriage co-axially with the table for swinging movement independently of the table, a segmental 80 rack on one of the arms, and gearing on the sub-carriage in mesh with said rack for swinging the carbon-carrier to draw the web rearward over the table for clearing the carbons 85 of the platen. 26. In a continuous billing typewriting machine, the combination of a carriage, a platen on the carriage, around which a composite web, comprising plies of work-sheets, 90 may be fed with interleaved carbon-sheets, a sub-carriage to travel with the platen-carriage, a curved table in normally inverted position on the sub-carriage, means for rotating the table against the web to draw out the web on the curved surface of the table, a carbon-carrier comprising a pair of supporting arms pivoted on the sub-carriage co-axially with the table for swinging movement independently of the table, a segmental 95 rack on one of the arms, and gearing on the sub-carriage in mesh with said rack for swinging the carbon-carrier to draw the web rearward over the table for clearing the carbons of the platen. 27. In a combined billing and typewriting machine, the combination with a carriage, of a platen around which may be fed a composite web of work-sheets interleaved with carbon, a segmental cylinder swinging concentrically from a pivot on the carriage to alternately place a slack and a stress in the web, a carbon-carrier mounted co-axially to 100 and co-operative with the cylinder to withdraw the carbon from the platen, and means to operate the carrier. 28. In a combined billing and typewriting machine, the combination of a carriage, a platen around which may be fed a composite 105 web of work-sheets interleaved with carbon, a segmental cylinder swinging concentrically from a pivot on the carriage to alternately place a slack and a stress in the web, a carbon-carrier mounted co-axially to 110 and co-operative with the cylinder to withdraw the carbon from the platen, and means to operate the carrier. 29. In a combined billing and typewriting machine, the combination of a carriage, a platen around which may be fed a composite 115 web of work-sheets interleaved with carbon, a segmental cylinder swinging concentrically from a pivot on the carriage to alternately place a slack and a stress in the web, a carbon-carrier mounted co-axially to 120 and co-operative with the cylinder to withdraw the carbon from the platen, and means to operate the carrier. 30. In a combined billing and typewriting machine, the combination of a carriage, a platen around which may be fed a composite 125 web of work-sheets interleaved with carbon, a segmental cylinder swinging concentrically from a pivot on the carriage to alternately place a slack and a stress in the web, a carbon-carrier mounted co-axially to 130 and co-operative with the cylinder to withdraw the carbon from the platen, and means to operate the carrier.

posite web of work-sheets interleaved with carbon, a segmental cylinder swinging concentrically from a pivot on the carriage, means to swing the cylinder between two stop positions, one position to provide a slack in the web during typing and the other position to provide a stress in the web when the typing is completed, a carbon-carrier mounted co-axially with the cylinder and raised by the stress in the web from a normal stop position, and means to restore the carrier to normal position and withdraw the web and carbon from the platen.

29. In a combined billing and typewriting machine, the combination of a carriage, a platen around which may be fed a composite web of work-sheets interleaved with carbon, a pivoted carrier to which are secured the rear ends of the carbon-sheets

adapted to withdraw the web and carbon from the platen, and means mounted co-axially with said carrier to render the carrier effective to withdraw said web and carbon from the platen.

30. In a combined billing and typewriting machine, the combination of a carriage, a platen around which may be fed a composite web of work-sheets interleaved with carbon, a pivoted carbon-carrier that is normally inoperative to control the carbon, and means for rendering the carrier operative to withdraw the typed web rearwardly and release the carbon from the platen comprising a segmental cylinder mounted co-axially with the carrier and shifted at will to stress the web between the carrier and the platen.

JOHN WALDHEIM
